Patented Dec. 4, 1923.

UNITED STATES PATENT OFFICE.

CECIL L. HORNING, OF LITTLE VALLEY, NEW YORK.

SAFETY RAZOR.

Application filed November 4, 1920. Serial No. 421,640.

To all whom it may concern:

Be it known that I, CECIL L. HORNING, a citizen of the United States, and resident of Little Valley, Cattaraugus County, State of New York, have invented certain new and useful Improvements in Safety Razors, of which the following is a specification.

My invention relates to safety razors and more particularly to that class thereof in which the blade is of substantially the form found in the usual ordinary razor and in which an attachment including a guard is detachably combined with said blade with the guard arranged to lie contiguous to the cutting edge thereof. Such guards or attachments, generally speaking, are combined with the blade by sliding them over the back thereof and are held in place by friction or by means of an elastic clamp of suitable construction. With such arrangements, the possibility of relative movement of the attachment lengthwise of the blade during use reduces the element of safety in razors thus equipped. Furthermore, an attachment of the indicated character, by being capable of being drawn from the blade with the guard in its operative position, also tends to dull and otherwise injure the blade. My invention contemplates the provision of a simple and novel construction in which the above disadvantages are overcome and in which lengthwise movement of the attachment, with the guard thereof in its operative position, is positively prevented and separation of said attachment from the razor blade is possible only after said guard has been adjusted to an inoperative position out of contact with the blade. A further object of my invention is to provide a structure in which the guard is capable of being applied to one side of the blade or the other, with means whereby said guard is firmly fixed against the cutting edge in either position. My invention will be fully described hereinafter and the features of novelty will be pointed out in the appended claims.

In the accompanying drawings, which illustrate an embodiment of my invention without defining its limits, Figure 1 is a side view of a razor provided with my improvements; Fig. 2 is an enlarged cross-section on the line 2-2 of Fig. 1; Figs. 3, 4 and 5 are detail views of the safety attachment separated from the razor and Fig. 6 is an enlarged section thereof on the line 6-6 of Fig. 4.

As shown in the drawings, the razor itself may be of the well known type commonly known as an ordinary razor and comprises a blade 10 having its shank 11 pivotally connected at 12 with the handle 13 in the customary manner. The attachment comprises a carrier 14 channelled in the direction of its length and adapted to be slipped upon the back of the blade 10 and held in place thereon by means of resilient converging clips 15 forming integral parts of said carrier and arranged to engage the sides of the blade as shown in Fig. 3. A plate 16, which, in the operative position of the parts, lies in surface engagement and in registry with the carrier 14, is pivotally connected therewith at 17 so as to be movable in a plane transverse to the plane of the blade 10. The plate 16, at its opposite ends, is provided with lugs 18 for the accommodation of trunnions 19 whereby the swinging guard 20 is hinged upon said plate 16, the guard being of any customary type and having the usual fingers or the like 21 adapted to extend beyond the cutting edge of the blade in the well known way.

With this arrangement, the guard 20 is reversible by being first swung to an inoperative position on its trunnions 19 after which the plate 16 is rotated about the pivot 17 to bring the guard to the opposite side of blade 10. In order to firmly fix the plate 16 in its adjusted positions in registry with the carrier 14, the latter may be provided with projections 22 arranged to fit into recesses 23 on the plate 16, the inherent resiliency of said plate being relied upon to snap the recesses and projections and to maintain them in operative connection with each other. The recesses 23 are preferably formed by depressing the material of which the plate 16 is made at the proper points, thus forming corresponding projections 23^a which, by co-operation with a flange 24 extending lengthwise of the guard 20 may serve to firmly fix the guard against the blade on either of its sides. To disconnect the recesses 23 and projections 22 or to release the flange 24 from the projections 23^a it is simply necessary to exert a force sufficient to overcome the resilient resistance of the parts.

For the purpose of securely fixing the attachment on the blade against relative movement in the direction of its length, when the guard 20 is in its operative position, said guard is provided at its opposite

end edges with lugs 25 arranged to extend over and engage the inner end edge or both end edges of the razor blade 10 as shown in Fig. 2. With this arrangement, it is impossible to slidably slip or withdraw the attachment from the razor blade when the guard is in engagement therewith; to permit any movement of the attachment in the direction of its removal, it is first necessary to swing the guard 20 to an inoperative position out of contact with the blade 10. Movement of the attachment relatively to the blade in a direction toward the handle 13 may be prevented either by the one lug 25 in co-operation with the outer end edge of the blade 10 or by means of an ear 26 depending from the carrier 14 over said end edge of the blade 10. The attachment is thus firmly fixed upon the blade against unintentional relative movement, thereby increasing the element of safety to a maximum degree; at the same time, by making it impossible to withdraw the attachment from the blade with the guard in an operative position, the possibility of dulling or otherwise injuring the delicate cutting edge of said blade 10 is obviated. The device is very simple in construction and provides an efficient and easily adjustable attachment whereby an ordinary razor may be readily converted into a safety razor.

Various changes in the specific form shown and described may be made within the scope of the claims without departing from the spirit of my invention.

I claim:

1. A safety attachment for razors comprising a carrier arranged to be slidably slipped upon the back of the razor blade in a lengthwise direction, a plate pivotally connected with said carrier to swing about an axis transverse to the cutting edge of the blade, a guard pivotally connected with said plate and movable about an axis parallel with said cutting edge in directions toward and away from the same to operative positions upon opposite sides of said razor blade in contact therewith and to inoperative positions out of contact with said blade and lugs located upon opposite end edges of said guard and partaking of the pivotal movements thereof, one of said lugs, in one or the other of the operative positions of said guard being arranged to project over the

inner end edge of the razor blade, to maintain the attachment against a sliding withdrawal from said blade when said guard is in either of its operative positions in contact with said blade. 55

2. A safety attachment for razors comprising a carrier arranged to be slidably slipped upon the back of the razor blade in a lengthwise direction, a plate pivotally connected with said carrier to swing about an axis transverse to the cutting edge of the blade, co-operating projections and recesses upon said carrier and plate whereby the latter is fixed against unintentional pivotal movement about said transverse axis relatively to said carrier, a guard pivotally connected with said plate and movable about an axis parallel with said cutting edge in directions toward and away from the same to operative positions upon opposite sides of said razor blade in contact therewith and to inoperative positions out of contact with said blade and lugs located upon opposite end edges of said guard and partaking of the pivotal movements thereof, one of said lugs, in one or the other of the operative positions of said guard being arranged to project over the inner end edge of the razor blade, to maintain the attachment against a sliding withdrawal from said blade when said guard is in either of its operative positions in contact with said blade. 60 65 70 75 80 85

3. A safety razor comprising a handle, a blade connected therewith, a carrier slidably mounted upon the back of said blade, a guard located upon said carrier and pivotally movable about an axis parallel with the cutting edge of the blade toward the same to an operative position in contact with said blade adjacent to said cutting edge and away from the latter to an inoperative position out of contact with said blade and a lug carried by said guard and partaking of the pivotal movements thereof, said lug, in the operative position of said guard, projecting over the inner end edge of said razor blade 100 to maintain said carrier and guard against withdrawal from said blade when the guard is in said operative position in contact with said blade. 90 95

In testimony whereof I have hereunto set my hand.

CECIL L. HORNING.
